(57) **CLAIM**

We claim the ornamental design for a fluid container, as shown and described.

DESCRIPTION

FIG. 1 is a top, front, and left side perspective view of a fluid container showing our new design;

FIG. 2 is a front elevational view thereof, the rear being identical;

FIG. 3 is a left side elevational view thereof the right side view being identical;

FIG. 4 is a top plan view thereof; and,

FIG. 5 is a bottom plan view thereof.
